UNITED STATES PATENT OFFICE.

WILLIAM BENNER, OF BRIDGEPORT, CONNECTICUT.

DESIGN FOR AN EGG STAND.

Application filed January 19, 1928. Serial No. 24,938. Term of patent 14 years.

To all whom it may concern:

Be it known that I, WILLIAM BENNER, a citizen of the United States, residing at 1275 Park Avenue, in the city of Bridgeport, in the county of Fairfield and State of Connecticut, have invented a new, original, and ornamental Design for Egg Stand, of which the following is a specification, reference being had to the accompanying drawing, forming part thereof, in which—

Figure 1 is a perspective view of an egg-stand showing my new design on the front portion thereof, and

I claim:

The ornamental design for an egg-stand, as shown.

WILLIAM BENNER.
